UNITED STATES PATENT OFFICE.

VICTOR HILDEBRAND, OF CONEMAUGH, PENNSYLVANIA.

WINDOW-SHADE AND CURTAIN-POLE BRACKET.

SPECIFICATION forming part of Letters Patent No. 740,431, dated October 6, 1903.

Application filed May 20, 1902. Renewed August 24, 1903. Serial No. 170,651. (No model.)

To all whom it may concern:

Be it known that I, VICTOR HILDEBRAND, a citizen of the United States, residing at Conemaugh, in the county of Cambria and State of Pennsylvania, have invented certain new and useful Improvements in Window-Shade and Curtain-Pole Brackets, of which the following is a specification.

This invention relates to brackets for supporting window-shades and curtain-poles.

The object of the invention is to construct a compound bracket which may be readily attached to window-frames of common construction and which may be adjusted to suit windows of various sizes.

The invention consists in certain constructions and combinations of mechanical elements, substantially as hereinafter described and claimed.

Figure 1 is a broken front elevation of brackets and support with curtain-pole approximately in position. Fig. 2 is a side elevation, partly in section, showing pole and shade-brackets and bracket-supporting bar.

Fig. 3 is a perspective view of one of the shade-brackets. Figs. 4 and 5 are front and rear views of bracket-supporting bar, partly broken away. Fig. 6 is a broken face view of part of one of the pole-brackets. Fig. 7 is a perspective view of attaching-screw.

The numeral 1 indicates the bracket-supporting end plate or bar. This end plate or bar is a flat piece of metal having a longitudinal slot 2 therein. A reinforcing-plate 5 is attached to the back of plate or bar 1. This reinforcing-plate 5 has a longitudinal slot 3 of greater width than slot 2 and lying with its axis in the same plane. The head 10 of a bracket-holding screw may be inclosed in slot 3, the body 11 of the screw passing through the slot 2 in bar 1. The bar 1 may be as long as desirable.

Supporting plates or bars 1 are attached at each side of the window-frame, the screw 11 projecting forward from each slot 2. The head 10 of the screw is flattened, so that the screw may not turn in the slot 2, but may slide bodily along said slot.

A shade-bracket 15 or 16 is applied to each of the supporting-bars and held thereto by a set-nut 12. The brackets 15 and 16 have the usual perforation and notch for holding a

shade. The base of each bracket has a flange 17 at each edge. These flanges nearly fit the edges of the plate or bar 1, so that the brackets are held with great firmness when the parts are assembled, as shown in Fig. 2.

The pole-brackets 20 are similar, and one is attached over each of the brackets 15 16, as shown in Fig. 1. Each bracket 20 is composed of a single strip of sheet metal bent or doubled on itself in the middle, thus forming a loop 21, which loop, projecting slightly alongside the edge of the shade-bracket, as in Fig. 1, tends to hold the pole against angular displacement when the parts are assembled.

The metallic strip forming bracket 20 is perforated or slotted, as at 22, near the return-bend through both leaves, and the holding-screw 11 passes through this slot. A little above the hole or slot the bracket bends outwardly, so as to project the curtain-pole beyond the plane of the shades. This outward bend of the pole-bracket may be as great as the relative position of the shade-brackets renders needful. The metal being flexible can be readily bent more or less and will afterward retain its shape under normal strains. Above the bend 22 the two leaves 23, and above this rivet the two layers of the strip run parallel for a little distance and then bend or turn away from each other, thus forming a clasp 24, in which the curtain-pole 25 rests. As the metal of bracket 20 is somewhat elastic, the clasp 24 will yield to embrace a larger pole than the normal size of the clasp would warrant, and the clasp will thus hold the pole with sufficient firmness, while yet permitting easy removal and adjustment. To still further hold the bracket 20 in upright position, the shade-brackets may have a small vertical flange 19, projecting from the edge of the shade-bracket close against one side of the pole-bracket. This insures stability of the parts when adjusted.

Whether the adjacent ends of the end plates 1 be connected and extend entirely across the window or not, the brackets 15 and 16 are adjustable toward and away from each other, so as to embrace shades of different length. Assuming the plates 1 1 to be held to a window-frame by screws 28 passing

through holes 4, the brackets 15 16 will be adjusted thereon by means of screws 11 and nuts 12 to such distance apart as to receive the shade. The brackets 20, held by the same nuts and screws against the outer faces of brackets 15 16, can also be adjusted in the same manner and when so adjusted will be ready to receive the curtain-pole and hold the same with a clamping pressure if the pole be 10 larger than the normal diameter of clasp 24.

What I claim is—

1. The combination with the slotted end plate and perforated shade-bracket, of a pole-bracket composed of a strip of sheet metal 15 doubled on itself in the middle and having a loop projecting alongside the shade-bracket, said pole-bracket being perforated through both leaves, and a screw passing through both brackets and the slot in the end plate.
2. The combination of the slotted end plate and the reinforcing-plate having a wider slot to retain the flattened head of the set-screw from turning, the shade-bracket having flanges embracing the edges of the end plate, and the set-screw and nut, substantially as described.
3. The combination of the slotted end plate,

the set-screw held against rotation therein, the perforated shade-bracket having flanges embracing the edges of the end plate and a flange at the edge of the pole-bracket, and the 30 pole-bracket having a passage for the set-screw, and the nut by which both brackets are held adjustably.

4. The combination with the slotted end plate, the shade-bracket, the pole-bracket 35 consisting of a strip of sheet metal bent in the middle and having a loop to bear against the edge of the shade-bracket, and a set-screw passing through the slot in the plate and holes in both brackets, and a nut on said screw. 40

5. The pole-bracket consisting of a strip of sheet metal doubled on itself and perforated near the bend, a bend or offset of the two leaves, means for holding the two leaves in contact, and a clasp formed by the outward 45 turn of the two ends of the strip.

In testimony whereof I affix my signature in presence of two witnesses.

VICTOR HILDEBRAND.
